UNITED STATES PATENT OFFICE.

CHARLES SCHWEIZER, OF BOSTON, MASSACHUSETTS.

FURNACE.

No. 921,169.

Specification of Letters Patent.

Patented May 11, 1909.

Application filed May 15, 1906. Serial No. 317,014.

To all whom it may concern:

Be it known that I, CHARLES SCHWEIZER, a citizen of the United States, residing at Boston, in the county of Suffolk and State 5 of Massachusetts, have invented certain new and useful Improvements in Furnaces; and I do hereby declare the following to be a full, clear, and exact description of the invention, such as will enable others skilled in the art 10 to which it appertains to make and use the same.

The object of my invention is the peculiar construction of a furnace, whereby there is complete combustion of the fuel and the 15 gases, effecting a saving of at least twenty-five per cent. of the fuel; an entire elimination of smoke; increased steaming capacity; greater evenness of heat; no deposit of soot or tar; at least forty per cent. less ash; a de- 20 cided saving of labor; and dryer steam, having greater expansive power.

With this object in view, the invention comprehends the novel construction, combination, and arrangement of parts of a de- 25 vice characterized by my invention, as will be hereinafter fully described in the specification, summed up in the claims, and illustrated in the drawings, in which latter:

Figure 1 is a longitudinal section of a fur- 30 nace constructed in accordance with the principles of my invention; Fig. 2 is a cross section on line 2—2, Fig. 1; Fig. 3 is a cross section on line 3—3, Fig. 1; and Fig. 4 is a cross section on line 4—4, Fig. 1.

Referring to the drawings, A designates an ordinary or any preferred type of boiler, properly supported in suitable settings, and having the usual tubes a. At the forward 35 end of the boiler and beneath the same is a fire-box, or combustion-chamber proper, B, entrance to which is through fuel-door b. An ordinary, or any preferred, form of grate b² separates the fire-box and the ash-pit b³, the latter being entered by a door b⁴, having, 40 desirably, an air-opening or openings b⁵ there- 45 through to support combustion. At the rear end of the grate, and extending from the bottom X of the furnace and terminating some distance short of the crown-sheet of 50 the boiler, is a bridge-wall C. At a suitable point to the rear of the bridge-wall C may be a wing-wall, D, extending from the crown- 55 sheet of the boiler, and terminating short of the bottom X of the furnace. This wing- wall is desirably supported by an arch d.

Some distance back of the wing-wall D is

a division-wall E, extending from the crown-sheet of the boiler entirely to the bottom X of the furnace. In this wall, toward the top thereof, is disposed a series of spaced 60 bars e of some suitable, highly-refractory substance, which serve to materially increase combustion by becoming incandescent and consuming the hitherto unburned products. Although it is desirably omitted in small 65 boilers, I prefer to use with large boilers a second wing-wall F, disposed in rear of division-wall E and near the rear end of the boiler, and extending, as shown, from the crown-sheet of the boiler and terminating 70 at a point below the plane of the additional combustion producers e, which wing-wall is preferably supported by an arch f.

The walls C and D form a passageway G, the walls D and E a passageway H, and the 75 walls E and F a passageway I. In the rear of wall F is a chamber J, leading to the boiler-tubes, and having a clean-out door j. Another clean-out door may be provided for the passageways G and H, as shown at g. 80

Into the passageway G, toward the bottom thereof, desirably extends a steam-pipe g², in communication with any suitable source of steam (not shown), and terminating at its inner end in a hollow bulb g³, preferably oval-shaped to shed ashes and dust falling thereupon; which bulb may have an exit-opening g⁴ in its top and exit-openings g⁵, g⁶ in its bottom; or, if desired, the top opening g⁴ may be omitted, as likely to be 90 filled with ashes, or clogged thereby. The function of this pipe g² is to furnish a quantum of steam, which materially assists combustion.

Into the passageway H, toward the bottom thereof, may project an air-pipe h², in communication, desirably, with the outside atmosphere, and terminating at its inner end in a similar hollow bulb h³, which may be provided with a top perforation h⁴ and with 95 bottom or side perforations h⁵, h⁶, as desired, the top perforation being omitted, if necessary. The object and function of this pipe h² is to furnish a sufficient quantity of fresh air to mingle with the partly consumed 100 products of combustion, thereby creating, as it were, a second fire.

Within the fire-box B, over the grate b², there are a series of spaced arches K, their tops being a short distance below the crown-sheet of the boiler, forming a passageway k 110 bounded by the crown-sheet of the boiler

and the tops of the arches. These arches are a very important and material feature of my invention, as will appear in the description of the operation presently to be described.

- 5 In the operation of my device, fire being started upon the grate, a good proportion of the gases are shunted through the spaces between the arches, to the space or passageway *k* beneath the crown-sheet of the boiler. Thus 10 the arches become chimneys to the fire, and the furnace a retort. The gases passing between the spaced arches, the latter, in a few minutes, become incandescent, or to a white heat, and, consequently, all the volatile matter and the streaky gases and moisture mingle there and become superheated, and the result is that no smoke is created. The spaces between the arches and the passageway *k* thereabove form, in reality, auxiliary 15 20 combustion-chambers, and the furnace becomes a perfect retort. As the gases and flames pass along the passageway *k* beneath the crown-sheet of the boiler, thus always keeping the boiler heated at this end, they 25 unite with the products of combustion passing directly over the bridge-wall *C*, and directly thereafter come into contact with the wing-wall *D*, which throws them back, causing a thorough intermixture of the gases and 30 ignition of unconsumed products of combustion. Thence passing downward, a quantum of steam issuing from the steam-pipe *g*² meets the gases, causing a fierce fire, the superheated gases then passing under the 35 arch *d* and mixing with the proper proportion of oxygen issuing from the air-pipe *h*², thus causing a re-ignition of partly consumed products. Thence the products pass between the spaced bars *e*, which causes a multiple 40 division of the products, and, as these bars soon become incandescent, they act to re-ignite all gases before separate carbon or smoke is produced. As the products issue from the additional combustion producers, 45 the consumption of the gases tends to produce a movement thereof, which induces a forced draft. After passing through the bars *e*, the gases and flames strike the second wing-wall *F*, causing a recoil, a whirling, 50 and a mixture of the products in their descent to the arch *f*, through which they finally pass up to and through the tubes *a* of the boiler *A*.

It is a point of my invention to effect a 55 rapid and constant intermixture of the unconsumed products of combustion and gases with the ignited products of combustion whereby complete combustion is effected before they enter the chimney in the course of their exit from the furnace. To this end, I 60 arrange, in the path of travel of the flame, a series of members, of varying form, but disposed at such relative distances apart that they will, each, effect a constant deflecting of 65 the unconsumed products and gases back

into the flame whereby such products and gases will be caused to become ignited, and, consumed. Immediately over the grate are the arches which are spaced and which operate, first, to deflect certain of the burning 70 and other gases and, secondly, to break them up. Then, the gases, etc., abut against the bridge-wall, which, likewise, tends to deflect the unconsumed products, etc., back into the flame to effect ignition of such of the gases as 75 have, so far, failed to become ignited. Next the gases and flame impinge against the division-wall which is rendered incandescent by the flame and, as the gases pass through this incandescent region, such of them which 80 had not become ignited will be ignited. The wing-wall is a further deflecting member tending to retard the travel of the gases in proximity to the division-wall to insure complete combustion of all of the traveling 85 gases, etc.

By this construction, a too quick exit of the products from the furnace into the boiler-tubes is prevented; in other words, their passage is retarded during their entire course 90 from the grate to the boiler-tubes, so that, finally, there is complete combustion, the gases and carbon being thoroughly mixed and consumed, preventing the great nuisance of smoke, and effecting a great saving of 95 fuel. All the fuel that ordinarily passes out through the stack is, in my device, saved and consumed.

Many practical tests of my furnace-construction demonstrate and establish the 100 claims which I have herein made for it.

Having thus fully described my invention, what I claim as new and desire to secure by Letters Patent is:

1. In a furnace, a boiler, a fire-box at one 105 end thereof, a grate in the fire-box, a series of equidistantly-spaced gas-deflecting arches in said fire-box disposed above the grate and removed from the boiler, a gas-deflecting and guiding bridge-wall at one end of the fire-box, 110 said bridge-wall terminating short of the boiler, and being removed from the arches but in the path of the flame and gases produced at the grate, a wing-wall in the rear of the bridge-wall, and extending from the aforesaid boiler down to a point slightly below the top of said bridge-wall, a division-wall back of the wing-wall and extending from the boiler entirely to the bottom of the furnace, said division-wall having passages transversely therethrough.

2. In a furnace, a boiler, a fire-box at one end thereof, a grate in the fire-box, a series of spaced gas-deflecting arches in said fire-box disposed over the grate and removed from the boiler, a gas - deflecting and guiding bridge-wall at one end of the fire-box, terminating short of the boiler and removed from said arches, a wing-wall in the rear of said bridge-wall and extending from the aforesaid 125

boiler to a point slightly below the bridge-wall, a division-wall back of the wing-wall and extending from the boiler entirely to the bottom of the furnace, said division-wall having an extended opening therethrough, and spaced bars of highly refractory material disposed in said opening and adapted to be rendered incandescent for effecting ignition of unconsumed products of combustion.

3. In a furnace, a boiler, a fire box at one end thereof, a grate therein composed of a plurality of spaced members, a series of spaced arches in the fire box, removed from the boiler and overlying the grate and adapted to effect a deflecting of the gases and unconsumed products of combustion toward the grate, a bridge-wall disposed at one end of the fire box, terminating short of the boiler, and removed from the arches but in the path of travel of the gases produced at the grate, a division-wall disposed back of the bridge-wall and having passages transversely through its central portion and adapted to be rendered incandescent by the flame produced at the grate, a wing-wall disposed contiguous to the division-wall and adapted to hold the gases temporarily in proximity to the division-wall.

4. In a furnace, a boiler, a fire-box at one end thereof, a grate therein composed of a plurality of spaced members, a series of spaced arches in the fire-box, overlying the grate and adapted to effect a deflecting of the gases and unconsumed products of combustion toward the grate, a bridge-wall disposed at one end of the fire-box, terminating short of the boiler, and removed from the arches but in the path of travel of the gases produced at the grate, a division-wall disposed back of the bridge-wall and having passages transversely through its central portion and adapted to be rendered incandescent by the flame produced at the grate, a wing-wall disposed contiguous to the division-wall and adapted to hold the gases temporarily in proximity to the division-wall, and steam and air pipes disposed between the bridge-wall and the division-wall in path of travel of the products of combustion.

In testimony whereof, I affix my signature, in the presence of two subscribing witnesses.

CHARLES SCHWEIZER.
